CLOTHES-WASHING MACHINE

Walter P. McCarty, Oak Park, Ill., assignor to
 General Electric Company, a corporation of
 New York

Application October 19, 1949, Serial No. 122,321

5 Claims. (Cl. 68—12)

1

The present invention relates to clothes washing machines, and more particularly, to improved electric control circuits for such washing machines of the semi-automatic type.

It has been proposed heretofore that a semi-automatic clothes washing machine might be provided in which the initial filling of the tub with wash water is manually controlled and in which the remainder of the controls of the machine to effect washing, rinsing and water extracting operations are performed automatically in a predetermined cycle by a timer governed program selector. Such a proposed machine offers many economies in manufacture as a consequence of the resulting simplification of the automatic controls and possesses certain advantages with reference to the supervision by the user of the filling of the tub with variable quantities of wash water at variable temperatures especially suited to the particular loads of clothes that are to be washed. However, the provision of both manual and automatic controls in such a washing machine would normally prove most confusing to the user and would ordinarily require elaborate interlocks to prevent improper operation.

Accordingly, it is a general object of the present invention to provide an improved semi-automatic clothes washing machine in which the initial filling of the tub with wash water is controlled manually and in which the remainder of the controls of the machine to effect washing, rinsing and water extracting operations are performed automatically in a predetermined cycle by a timer governed program selector.

Another object of the invention is to provide in a semi-automatic washing machine of the type noted, an improved and exceedingly simple control arrangement requiring the user to manipulate only a single control member.

Another object of the invention is to provide in a semi-automatic washing machine of the type noted, an improved control arrangement including a manually operable control member or dial mounted for rotary movements to preselect any one of the several operations of the machine and mounted for axial movements selectively to initiate and to arrest the performance of the pre-selected one of the several operations of the machine.

A further object of the invention is to provide in a clothes washing machine including an upstanding casing, an upstanding tub arranged in the casing and mounted for rotation, an upstanding agitator arranged in the tub and

2

mounted for oscillation, and a pump operative to deliver from the casing any water caught therein that is overflowed from the tub as a result of an excess filling thereof, or that is centrifuged from the tub as a result of rotation thereof, an improved arrangement that is responsive to the initiation of any one of the several different filling, washing, rinsing, and water extracting operations of the machine for initiating operation of the pump.

A still further object of the invention is to provide in a washing machine of the type noted, an improved electric control system for effecting and for interlocking both the various manually controlled operations and the various automatically controlled operations of the machine.

Further features of the invention pertain to the particular arrangement of the elements of the clothes washing machine and the electric control system therefor, whereby the above-outlined and additional operating features thereof are attained.

The invention, both as to its organization and method of operation, together with further objects and advantages thereof, will best be understood by reference to the following specification taken in connection with the accompanying drawings, in which Figure 1 is a vertical sectional view of a clothes washing machine embodying the present invention, Fig. 2 is another vertical, sectional view of the machine, taken in the direction of the arrows along the offset line 2—2 in Fig. 1; Fig. 3 is an enlarged vertical sectional view of solenoid controlled valve mechanism incorporated in the machine, taken in the direction of the arrows along the line 3—3 in Fig. 2; Fig. 4 is an enlarged fragmentary plan view of the left rear portion of the top wall of the casing of the machine shown in Figs. 1 and 2, illustrating the manually operable control dial incorporated therein for controlling operation thereof; Fig. 5 is an enlarged exploded fragmentary vertical sectional view of the control dial and the connected program controller switch incorporated in the machine for controlling operation thereof, taken in the direction of the arrows along the line 5—5 in Fig. 4; Fig. 6 is an enlarged vertical sectional view of the program controller switch, taken in the direction of the arrows along the line 6—6 in Fig. 5; and Fig. 7 is an electric diagram of the program controller switch and the circuit control arrangement incorporated in the machine shown in Figs. 1 and 2. Referring now to Figs. 1 and 2 of the drawings there is generally illustrated a clothes washing

machine 10 of the oscillating agitator and rotating tub type embodying the present invention. Specifically, the machine 10 is of the general construction and arrangement of that disclosed in U. S. Patent No. 2,513,844, granted on July 4, 1950, to George P. Castner and Arthur D. Lund, and comprises an upstanding casing 11 including upper and lower sections 12 and 13, the casing sections 12 and 13 being suitably detachably secured together, a surrounding gasket 14 formed of rubber, or the like, being disposed at the junction therebetween. The casing sections 12 and 13 are generally square in horizontal cross section with rounded corners connecting the various walls thereof. The upper casing section 12 is supported directly upon the lower casing section 13; and the lower casing section 13 is supported upon four vertically adjustable feet 15 respectively arranged at the four rounded corners thereof and respectively engaging four mounting pads 16 formed of linoleum, or the like, and suitably secured to a floor or other external support. The upper casing section 12 includes connected front and rear walls 17 and 18, side walls 19 and 20, and top and bottom walls 21 and 22; while the lower casing section 13 includes front and rear walls 23 and 24, side walls 25 and 26, and a bottom wall 27. Thus the bottom wall 22 of the upper casing section 12 constitutes a dividing wall between the upper and lower casing sections 12 and 13; whereby the upper casing section 12 defines a tub and water receiving compartment 28, and the lower casing section 13 defines a machinery compartment 29.

Within the machinery compartment 29 there is disposed a frame 30 upon which the principal component elements of the apparatus are mounted, the frame 30 being provided with a substantially centrally disposed and downwardly directed foot 31 arranged in an associated bearing 32, that is, in turn, supported by a resilient bushing 33 formed of rubber, or the like, and disposed in a depression 34 formed in the bottom wall 27 of the lower casing section 13. The frame 30 is thus resiliently supported for limited longitudinal movement in the vertical direction and is also capable of limited gyratory or wobbling movement about the longitudinal axis of the machine 10. In order to center the frame 30 along the longitudinal axis of the machine 10 and in its upstanding position, four radially extending and angularly spaced-apart tension springs 35 are arranged below the bottom wall 22 of the upper casing section 12 and extend between four posts 36 carried by the frame 30 and four adjustable eye bolts 37 carried by four brackets 38 that are secured to the walls of the lower casing section 13 adjacent to the four rounded corners between the front and rear walls 23 and 24 and the side walls 25 and 26. Also, in order to limit the gyratory movement of the frame 30 about the foot 31 and about the longitudinal axis of the machine 10, four radially extending and angularly spaced-apart snubbers 39 are provided between the frame 30 and four brackets 40 respectively secured to the front and rear walls 23 and 24 and the side walls 25 and 26 of the lower casing section 13.

The frame 30 carries an upstanding longitudinally extending barrel 41 projecting from the machinery compartment 29 through an opening 42 provided in the central portion of the bottom wall 22 into the tub compartment 28, the opening 42 being surrounded by an upstanding tubular sleeve 43 arranged in spaced relation to the barrel 41 and joined to the bottom wall 22. Within the

barrel 41 there is mounted a rotatable sleeve 44, the upper and lower ends of the sleeve 44 being suitably journaled upon upper and lower anti-friction bearings 45 and 46 arranged within the respective upper and lower ends of the barrel 41. The upper end of the sleeve 44 terminates in an annular flange 47 to which there is secured by a number of bolts 48 an upstanding tub 49, the tub 49 being arranged entirely within the tub compartment 28. The lower end of the sleeve 44 has rigidly secured thereto a pulley 51 arranged within the machinery compartment 29. Thus, it will be understood that when the pulley 51 is rotated that the sleeve 44 is rotated effecting rotation of the tub 49. The tub 49 comprises a substantially centrally disposed downwardly extending conical bottom element 52 terminating in an annular sediment trap structure 53. Also, the tub 49 includes an outwardly directed bottom wall 54 surrounding the annular trap structure 53 and merging into an upwardly tapered side wall 55, a heavy balance ring 56 being secured to the upper edge of the side wall 55. The balance ring 56 is provided with an inwardly directing flange 57 having a substantially centrally disposed opening 58 formed therein for the purpose of rendering the interior of the tub 49 accessible from the exterior, the flange 57 preventing clothes from being flung from the tub 49 incident to rotation thereof. The lower portion of the balance ring 56 is provided with a number of serrations in order to define a number of openings 59 between the lower portion thereof and the upper edge of the side wall 55 of the tub 49 in order to accommodate the passage of water therethrough as a result of the centrifugal forces when the tub 49 is rotated. Further, two outwardly and then upwardly extending tubes 60 are carried upon the exterior of the tub 49 at substantially diametrically disposed positions, the lower ends of the tubes 60 communicating with the sediment trap structure 53 and the upper ends of the tubes 60 discharging into cooperating grooves 61 formed in the balance ring 56 and communicating with the tub compartment 28. Further, it is pointed out that the sediment trap structure 53 comprises an inwardly directed throat or flange member 62 joining the bottom wall 54 of the tub 49 and overhanging the lower ends of the tubes 60. It will be understood that any sediment accumulating in the sediment trap 53 will be discharged through the tubes 60 into the tub compartment 28 incident to rotation of the tub 49 as a consequence of the centrifugal forces produced.

A longitudinally extending upstanding shaft 63 is suitably journaled in a centrally disposed opening formed in the sleeve 44, the upper end of the shaft 63 projecting through a tubular extension 64 carried by the conical bottom element 52 of the tub 49. The upper end of the shaft 63 is journaled in and supported upon a bearing element 65 arranged in the upper end of the tubular extension 64; and the lower end of the shaft 63 is located with respect to the lower end 66 of the sleeve 44 by a bearing 66 that is positioned by a collar 68 which is detachably secured to the lower end of the shaft 63. The extreme upper end of the shaft 63 has detachably secured thereto by a fixture 69 an upstanding bladed agitator 70 arranged in the tub 49 and surrounding the tubular extension 64. The agitator 67 includes a substantially conical shaped body 68 terminating in an annular flange 69 disposed over the inwardly directed throat member 62. The lower end of the body 68 of the agitator 67 carries

three upstanding angularly spaced-apart main clothes agitating blades 78; and the upper end of the body 68 of the actuator 67 carries three intervening angularly spaced-apart auxiliary suds agitating vanes 71. The junction between the main vanes 70 and the auxiliary vanes 71 on the agitator 67 being arranged adjacent to the normal water level in the tub 49 indicated by the dash line 72.

Also the frame 30 carries an oscillating mechanism 73 that is preferably of the character of that disclosed in U. S. Patent No. 1,964,440, granted on June 26, 1934, to Allen J. Patch. The oscillating mechanism 73 includes a casing 74 in which there is journalled an upstanding shaft 75 that projects therethrough. The shaft 75 carries a crank arm 76 that is oscillated by associated parts, not shown. The shaft 75 is arranged along the longitudinal axis of the machine 10 coincident with the longitudinal axis of the shaft 63; and clutch mechanism 77 is interposed between the upper end of the shaft 75 and the lower end of the shaft 63. Specifically, the clutch mechanism 77 comprises cooperating clutch elements 78 and 79 respectively carried by the upper end of the shaft 75 and by the lower end of the shaft 63. The clutch element 78 is splined upon the upper end of the shaft 75 for longitudinal sliding movement thereon toward and away from the cooperating clutch element 79 rigidly secured to the lower end of the shaft 63 in order to effect engagement and disengagement of the clutch elements 78 and 79. The mechanism 77 further comprises a bell crank 80 carried by the frame 30, one end of the bell crank 80 cooperating with the clutch element 78, and the other end of the bell crank 80 cooperating with the armature of a solenoid 81, also carried by the frame 30. It will be understood that when the solenoid 81 is energized the bell crank 80 is operated to clutch the elements 78 and 79; and when the solenoid 81 is de-energized the bell crank 80 is returned to its normal position in order to declutch the elements 78 and 79. When the clutch mechanism 77 occupies its clutched position the oscillating mechanism 73 effects oscillation of the shaft 63 and the consequent oscillation of the agitator 67 with respect to the tub 49.

Further, the frame 30 carries within the machinery compartment 29 a main electric motor 82 provided with a rotatable operating shaft 83 carrying two pulleys 84 and 85 on the upper end thereof, and a drain pump 86 provided with an operating shaft 87 carrying a pulley 88 on the upper end thereof. The pulley 84 carried by the operating shaft 83 of the main motor 82 is belted by a V-belt 89 to the pulley 88 carried by the operating shaft 87 of the drain pump 86; and the pulley 85 carried by the operating shaft 83 of the main motor 82 is belted by a V-belt 90 to a pulley 91 secured to the operating shaft, not shown, of the oscillating mechanism 73. Thus it will be understood that when the main motor 82 is operated the drain pump 86 is operated and also the oscillating mechanism 73 is operated; however, oscillation of the shaft 63 and the agitator 67 by the operating oscillating mechanism 73 are dependent upon the position of the clutch mechanism 77. Also, the drain pump 86 includes an intake connection 92 and a discharge connection 93. The intake connection 92 is suitably connected by a section of hose 94 formed of rubber, or the like, to a downwardly directed drain connection 94 provided in the bottom wall 22 of the upper casing section 12; and the discharge connection 93 is suitably connected to a

discharged conduit 95 projecting through an opening 96 formed in the rear wall 24 of the lower casing section 12. Of course, it will be understood that when the drain pump 86 is operating any water accumulating in the upper casing section 12 will pass through the drain connection 94 and the hose 93 into the intake connection 92, and will be pumped from the discharge connection 93 via the drain conduit 95 to the exterior of the machine 10.

Further, within the machinery compartment 29 the frame 30 supports an electric spin motor 97 that is provided with an operating shaft 98 that is connected to a fluid drive or coupling mechanism 99 of the character of that disclosed in the previously mentioned Castner and Lund patent. Specifically, the fluid drive mechanism 99 includes a rotatable casing 100 carrying a pulley 101 that is connected by a V-belt 102 to the pulley 51 that is carried by the sleeve 44. Specifically, the rotatable casing 100 is bladed and contains a quantity of fluid or hydraulic medium, such as oil, that cooperates with an enclosed bladed member that is directly secured to the upper end of the operating shaft 98 of the spin motor 97. Thus, it will be understood that when the spin motor 97 is operated the operating shaft 98 effects rotation of the casing 100 of the fluid mechanism 99 through the intermediary of the quantity of oil cooperating with the bladed elements noted, whereby the pulley 101 is rotated effecting rotation of the pulley 51 and the consequent rotation of the sleeve 44 and the tub 49. This arrangement of the fluid coupling 99 insures gradual acceleration of the tub 49 to its full spinning speed when operation of the spin motor 97 is initiated, and also permits an automatic slowdown of the tub 49 in its spinning operation in the event it contains an unbalanced load of clothes, as disclosed in the previously mentioned Castner and Lund patent.

The top wall 21 of the upper casing section 12 has a substantially centrally disposed square opening 104 formed therein in order to render the interior of the tub 49 accessible from the exterior of the machine 10, the opening 104 being surrounded by a downwardly directed substantially square flanged throat 105 preventing the presentation of sharp edges. The opening 104 formed in the top wall 21 is surrounded by a counterdepression 106 of substantially square form that receives an associated hinged cover 107, the cover 107 being hinged adjacent to the rear portion of the counterdepression 106 in any suitable manner, not shown. Also, the rear wall 18 and the rear portion of the top wall 21 of the upper casing section 12 carry a substantially L-shaped hood 108 in which there is arranged an inlet conduit 109, the front end of the inlet conduit 109 projecting through a hole 110 formed in the top wall 21 and overhanging the adjacent upper edge of the tub 49. The rear end of the inlet conduit 109 is connected by a suitable length of hose 111 formed of rubber, or the like, to inlet valve mechanism 112 disposed within the machinery compartment 29, the hose 111 passing through a hole 113 formed in the rear wall 24 of the lower casing section 12.

As best shown in Figs. 2 and 3, the inlet valve mechanism 112 comprises a casing 114 provided with partition structure 115 defining a cold water inlet chamber 116, a hot water inlet chamber 117 and a mixing chamber 118. The cold water inlet chamber 116 and the hot water inlet chamber 117 are respectively provided with a cold water inlet connection 119 and a hot water in-

let connection 120. The connections 119 and 120 projecting through the hole 96 formed in the rear wall 24 of the lower casing section 13. The mixing chamber 118 comprises the outlet connection 121 that is directly connected to the lower end of the hose 111 as previously noted. Valve ports 122 and 123 are formed in the partition structure 115 and respectively communicate with the cold water inlet chamber 116 and with the hot water inlet chamber 117 and commonly communicate with the mixing chamber 118. The valve ports 122 and 123 are respectively provided with cooperating valve elements 124 and 125 carried on the lower ends of respective valve stems 126 and 127 projecting through openings provided in the casing 114. Also the casing 114 supports two solenoids 128 and 129 that are respectively provided with armatures that are respectively connected to the valve stems 126 and 127. In the valve mechanism 112 the valve stems 126 and 127 are normally biased by springs, not shown, in the upper direction so that the respectively carried valve elements 124 and 125 normally close the respective valve ports 122 and 123. When the solenoid 128 is energized the armature thereof moves downwardly forcing the valve stem 126 downwardly against its normal bias in order to move the valve element 124 to unseat the associated valve port 122, whereby the interior of the cold water inlet chamber 116 is placed into communication with the interior of the mixing chamber 118. Similarly, when the solenoid 129 is energized the armature thereof moves downwardly forcing the valve stem 127 downwardly against its normal bias in order to move the valve element 125 to unseat the associated valve port 123, whereby the interior of the hot water inlet chamber 117 is placed into communication with the interior of the mixing chamber 118. Accordingly, it will be understood that when the cold water solenoid 128 is energized alone, cold water is supplied from the mixing chamber 118 of the valve mechanism 112 to the inlet conduit 109; when the hot water solenoid 129 is energized alone, hot water is supplied from the mixing chamber 118 of the valve mechanism 112 to the inlet conduit 109; and when both the cold water solenoid 128 and the hot water solenoid 129 are energized, warm water is supplied from the mixing chamber 118 of the valve mechanism 112 to the inlet conduit 109. Of course, the water that is supplied from the valve mechanism 112 to the inlet conduit 109 issues from the front end thereof and falls into the open top of the tub 49.

For the purpose of controlling the various operations of the machine 10 a single manually operable control dial 130 is carried by the top wall 21 adjacent to the rounded corner at the junction between the rear wall 18 and the left-hand side wall 26 of the upper casing section 12, and a program selector switch 131 is arranged in the machinery compartment 29 and supported upon a bracket 132 carried by the left-hand side wall 26 of the lower casing section 13, the manually operable control dial 130 being operably connected to the program selector switch 131 by an arrangement including a longitudinally extending control rod 133 projecting through the tub compartment 28. More particularly, as shown in Figs. 1, 4 and 5, a longitudinally extending tube 134 surrounds the control rod 133, the upper and lower ends of the tube 134 being securely anchored in upper and lower grommets 135 and 136 respectively anchored in openings respectively formed in the top wall 21 and in the

bottom wall 22 of the upper casing section 12. The grommets 135 and 136 are formed of rubber, or the like, and are hermetically sealed in the openings respectively formed in the top wall 21 and in the bottom wall 22 and to the respective upper and lower ends of the tube 134 in order positively to insure fluid-tight joints and to render passage of the control rod 133 through the tub compartment 28 out of contact with any water contained therein. The lower end of the control rod 133 projects into the machinery compartment 29 and is threaded in order to receive a fixture 137, that, in turn, is secured by an insulating sleeve 138 to an operating shaft 139 projecting from the casing 140 of the program selector switch 131.

The manually operable control dial 130 comprises an upper knob 141 and a lower outwardly flanged skirt 142. The body portion of the skirt 142 has a central disposed opening through which the extreme upper end of the control rod 133 projects, the body portion of the skirt 142 being secured to the extreme upper end of the control rod 133 by an arrangement including a plate 143 and a plurality of screws 144 extending through openings provided in the body portion of the skirt 142 and threaded into cooperating openings provided in the plate 143. This arrangement for securing the skirt 142 to the upper end of the control rod 133 permits initial relative rotation and adjustment of the position of the skirt 142 with respect to the position of the control rod 133 so that the initial positions of the skirt 142 and the control rod 133 may be adjusted in order to bring their "zero" or "off" positions into initial registry, for a purpose more fully explained hereinafter. The body portion of the knob 141 is provided with a centrally disposed opening therein that is threaded and directly receives the extreme upper end of the control rod 133 that is provided with a threaded section 145 on the extreme upper end thereof. The threaded section 145 of the control rod 133 is provided with the threads mentioned which are pitched in the clockwise direction, as viewed in Fig. 4, so that when the knob 141 is rotated in the clockwise direction, it is tightened on the threaded end 145 of the control rod 133 and frictionally engages the skirt 142 in order to effect rotation of the control rod 133 and the skirt 142 in the clockwise direction. On the other hand, in the event the knob 141 is rotated in the counterclockwise direction, as viewed in Fig. 4, it is merely unscrewed from the threaded end 145 of the control rod 133, thereby preventing rotation of the control rod 133 in the counterclockwise direction mentioned. As previously noted, the lower end of the control rod 133 is threaded in order to receive the fixture 137, which arrangement permits of initial adjustment in the longitudinal direction of the initial position of the control rod 133 with respect to the operating shaft 139 of the program selector switch 140, for a purpose more fully explained hereinafter. The peripheral portion of the outwardly flanged skirt 142 carries indicia 146, explained more fully hereinafter, that cooperates with an index pointer 147 that is carried by the upper surface of the top wall 21, whereby the rotary position of the manually operable control knob 141 and consequently the control rod 133 may be appropriately indexed.

As shown in Fig. 6, the program selector switch 131 comprises the principal casing 140 housing the operating shaft 139 projecting from the top

wall thereof, as previously noted. Also the program selector switch 131 comprises five insulating control cams C1, C2, C3, C4 and C5 arranged in longitudinally spaced-apart relation and rigidly secured to the operating shaft 139, which control cams respectively cooperate with five contact sets or switches S1, S2, S3, S4 and S5, for the purpose of selectively controlling the various electrical circuits of the machine 10 in response to selective rotation of the operating shaft 139. Also, the operating shaft 139 carries below the lowermost control cam C1 an insulating plunger or actuator 148 that cooperates with a master or line switch LS. In addition to rotary movements the operating shaft 139 is mounted for limited longitudinal movements so that the actuator 148 selectively controls the line switch LS. Specifically, when the operating shaft 139 is lifted or moved to its upper position, the actuator 148 disengages the lower spring of the line switch LS permitting operation of the line switch LS to its closed circuit position due to its inherent resiliency; and, on the other hand, when the operating shaft 139 is depressed or moved to its lower position the actuator 148 engages the lower spring of the line switch LS forcing the line switch LS into its open circuit position. The operating shaft 139 may be restrained in its upper and lower positions in any suitable manner, such, for example, as by the friction in the supporting bearings. Moreover there may be provided an arrangement including a substantially U-shaped spring 148a that cooperates with the actuator 148 for the purpose noted.

Further, the program selector switch 131 comprises an auxiliary casing 149 housing a timer of the Mallory type and provided with an operating shaft 150' projecting from the auxiliary casing 149 into the principal casing 140. The Mallory time timer includes an electric timer motor 150 of the shaded pole type that is operated at a synchronous speed from a 60 cycle 110 volts A. C. source, as well as escapement mechanism 151 that is so connected and arranged that when the timer motor 150 is continuously operated the operating shaft 150' is released each half minute, and rotates upon each release thereof $\frac{1}{2}$ revolution. The details of the Mallory timer have not been disclosed as they are entirely conventional and form no part of the present invention.

The extreme upper end of the operating shaft 150' of the Mallory timer projecting into the principal casing 140 has a pinion 152 rigidly secured thereto that cooperates with a gear 153 that is rigidly secured to a shaft 154 mounted within the casing 140. A pinion 155 is rigidly secured to the shaft 154 and cooperates with a gear 156 rigidly secured to a shaft 157 mounted in the casing 140. A gear 158 is rigidly secured to the extreme lower end of the operating shaft 139 and cooperates with a pinion 159 rigidly secured to a shaft 160 mounted in the casing 140. The shafts 157 and 160 are arranged in longitudinal alignment and are mounted for independent rotation with respect to each other. Finally, a ratchet wheel 161 is rigidly secured to the shaft 160 and cooperates with an associated pawl 162 pivotally mounted upon a pin 163 carried by the gear 156. The arrangement of the pawl and ratchet mechanism 161-162 between the shafts 157 and 160 permits selective overriding and clutching therebetween and consequent selective overriding and clutching between the operating shafts 139 and 150' as explained more fully below.

When the manually operable control dial 130 is rotated in the clockwise direction, as viewed in Fig. 4, the control rod 133 and consequently the operating shaft 139 and the gear 158 are rotated therewith. Rotation of the gear 158 in the clockwise direction effects rotation of the pinion 159 in the counterclockwise direction, whereby the ratchet wheel 161 rotates therewith slipping over the pawl 162 so that the rotation of the pinion 159 in the counterclockwise direction does not in any way interfere with the operating or non-operating condition of the timer motor 150. On the other hand, when the timer motor 150 is operated the escapement mechanism 151 effects rotation of the operating shaft 150' step-by-step in the counterclockwise direction, whereby the pinion 152 drives the gear 153 in the clockwise direction. As the gear 153 is driven in the clockwise direction, the pinion 155 drives the gear 156 in the counterclockwise direction, whereby the pawl 162 catches the ratchet wheel 161 driving the pinion 159 in the counterclockwise direction. The pinion 159 driven in the counterclockwise direction drives the gear 158 in the clockwise direction, whereby the operating shaft 139 and consequently the control rod 133 and the dial 130 are rotated in the clockwise direction. It will be understood that when the timer motor 150 is operating the operating shaft 141 is driven step-by-step each $\frac{1}{2}$ minute, whereby the control dial 130 is correspondingly driven step-by-step each $\frac{1}{2}$ minute further in the clockwise direction, as viewed in Fig. 4, from its initial position after manual setting thereof in the clockwise direction into a preselected one of its control positions, as explained more fully hereinafter.

The connection and arrangement of the electric control network for the various elements of the washing machine 10 will best be understood by reference to Fig. 7, wherein there is illustrated diagrammatically both the various operating elements of the machine 10 and the electric network, as well as a time-sequence operating chart therefor indicating the coordinated controls exercised by the control cams C1 to C5, inclusive, upon the associated sets of switch springs S1 to S5, inclusive, to produce a cycle of operation of the machine 10. In the circuit network it is assumed that the negative line conductor 170 of the source of current supply is connected to ground potential in the machine 10 and that the positive line conductor 171 of the source of current supply is insulated from ground potential, the current supply comprising a commercial 60 cycle 110 volts A. C. source.

The line switch LS comprises two individual springs one of which is connected to the positive line conductor 171 and the other of which is connected to a bus 172, the two individual springs mentioned being normally biased toward engagement with each other. The switch S1 comprises two individual springs one of which is connected to the bus 172 and the other of which is connected to one terminal of the hot water solenoid 129, the two individual springs mentioned being normally biased toward disengagement with each other. The other terminal of the hot water solenoid 129 is connected to the negative line conductor 170 to provide a first electric control circuit. The switch S2 comprises two individual springs one of which is connected to the bus 172 and the other of which is connected to one terminal of the cold water solenoid 128, the two individual springs mentioned being normally biased toward disengagement with each other. The

other terminal of the cold water solenoid 128 is connected to the negative line conductor 170 to provide a second electric control circuit. The switch S3 comprises two individual springs one of which is connected to the bus 172 and the other of which is connected to one terminal of the main motor 82, the two individual springs mentioned being normally biased toward disengagement with each other. The other terminal of the main motor 82 is connected to the negative line conductor 170 to provide a third electric control circuit. The switch S4 comprises two individual springs one of which is connected to the bus 172 and the other of which is connected to one terminal of the timer motor 150, the two individual springs mentioned being normally biased toward disengagement with each other. The other terminal of the timer motor 150 is connected to the negative line conductor 170 to provide a fourth electric control circuit. The switch S5 comprises three individual springs the main or center spring of which is connected to the bus 172, the lower spring of which is connected to one terminal of the clutch magnet 81, and the upper spring of which is connected to one terminal of the spin motor 97, the center spring mentioned being normally biased away from the upper spring mentioned and toward the lower spring mentioned. The other terminal of the clutch magnet 81 is connected to the negative line terminal 170 to provide a fifth electric control circuit; and the other terminal of the spin motor 97 is connected to the negative line terminal 170 to provide a sixth electric control circuit.

The program control switch 131 comprises a plurality of coordinate positions corresponding to the positions of the manually operated control dial 130 and angularly disposed in the rotary direction coincident with the corresponding indicia 146 provided on the skirt 142 of the control dial 130 and cooperating with the index pointer 147. Specifically, the control dial 130 and the program selector switch 131 comprises coordinate "off" positions so that the legend "off" on the skirt 142 cooperates with the index pointer 147 when the program selector switch 131 occupies its "off" position, this initial registry being effected by the initial adjustment of the skirt 142 upon the upper end of the control rod 133 by virtue of the adjustability of the plate 143 cooperating with the screws 144, as previously noted. When the program selector switch 131 occupies its "off" position the lower springs of the switches S1, S2, S3 and S4 disengage the respectively associated upper springs thereof, and the center spring of the switch S5 disengages both of the associated upper and lower springs thereof, by virtue of the cooperation of the control cams C1 to C5, inclusive, with the respectively associated switches S1 to S5, inclusive. Also, the control dial 130 normally occupies its depressed or lower position, whereby the actuator 148 forces the line switch LS into its open circuit position. Also, the control dial 130 and the program selector switch 131 comprise coordinate "hot fill" positions, "warm fill" positions, "cold fill" positions, and a plurality of "control" positions angularly disposed with respect to the coordinate "off" positions thereof, the correlation of the various positions being explained more fully below. Specifically, as viewed in Fig. 4, the "hot fill" position of the control dial 130 is disposed 10° in the counter-clockwise direction with respect to the "off" position thereof; and, as viewed in Fig. 7, the "hot

fill" position of the program selector switch 131 is disposed 10° toward the right with respect to the "off" position thereof. The coordinate "hot fill" positions of the control dial 130 and the program selector switch 131 continue 15° further in the directions noted to the 25° positions thereof; at which positions coordinate "warm fill" positions of the control dial 130 and the program selector switch 131 begins and then continues 15° further in the directions noted to the 40° positions thereof; at which positions coordinate "cold fill" positions of the control dial 130 and the program selector switch 131 begins and then continues 15° further in the directions noted to the 55° positions thereof; and at which positions coordinate first "control" positions thereof begin. The various coordinate "control" positions of the control dial 130 and the program selector switch 131 continue 305° further in the directions noted to the 360° or 0° positions thereof, the last-mentioned coordinate positions comprising the "off" positions thereof. As explained more fully hereinafter, the movements of the control dial 130 and the program selector switch 131 into the various coordinate "hot fill," "warm fill" and "cold fill" positions thereof in the first 55° in the directions noted are governed entirely manually by the user of the machine 10 as a result of rotation of the knob 141 provided on the control dial 130; while the movements of the control dial 130 and the program selector switch 131 into the various coordinate "control" positions thereof in the next 305° in the directions noted are governed either manually by the user in the manner noted above, or automatically by the timer motor 150. In other words, as explained more fully hereinafter, when the control dial 130 and the program selector switch 131 are rotated 55° away from their coordinate "off" positions, the fourth control circuit for operating the timer motor 150 is selected as a result of the cooperation between the control cam C4 and the switch S4 so that operation of the timer motor 150 may be initiated, whereby the timer motor 150 upon operating continues the rotation of the control dial 130 and the program selector switch 131 automatically through the various coordinate "control" positions thereof at the predetermined time rate and back into the coordinate "off" positions thereof. Accordingly, the first 55° of rotation of the control dial 130 constitutes the manual control segment thereof and the next 305° of rotation of the control dial 130 constitutes the automatic cycle control segment thereof. When the control dial 130 is rotated to any one preselected position, the program selector switch 131 is rotated to the coordinate one preselected position, whereby the control cams C1 to C5, selectively govern the respective switches S1 to S5 in order to preselect a certain one or more of the six electric control circuits. At this time when the control dial 130 is lifted from its lower position into its upper position, the actuator 148 effects closure of the line switch LS, whereby the positive line conductor 171 is connected to the bus 172 in order to effect energization of one or more of the previously selected electric control circuits, so that operation of the machine 10 is initiated to perform the operating functions corresponding to the preselected electric control circuits mentioned.

In order to illustrate an example of the manual controls that may be performed by the user of the machine 10, let it be assumed that the machine 10 is at rest and that it is desired to

fill the tub 49 with hot wash water, the user rotates the control dial 130 in the clockwise direction, as viewed in Fig. 4, into its "hot fill" position, the segment between 10° and 25° thereon, and then lifts the control dial 130 into its upper position. When the control dial 130 is rotated into its "hot fill" position, as noted above, the control cam C1 closes the switch S1 to preselect the first electric control circuit for the hot water solenoid 129; and when the control dial 130 is lifted into its upper position, the line switch LS is closed in order to complete the preselected first electric control circuit effecting energization of the hot water solenoid 129. The hot water solenoid 129 operates to effect the supply of hot water from the inlet valve mechanism 112 to the inlet conduit 109 and thence into the tub 49 in the manner previously explained. When the desired quantity of hot wash water has been admitted to the tub 49, the user merely depresses the control dial 130 effecting opening of the line switch LS, whereby the hot water solenoid 129 is de-energized in order to operate the inlet valve mechanism 112 to its closed position, as previously explained. Normally, the tub 49 is filled with wash water up to the dash line 72 after the clothes have been placed in the tub 49; and at this time the user then places the detergent into the tub 49 and closes the cover 107, the cover 107 having been in its open position to accommodate placement of the clothes in the tub 49. In view of the foregoing, it will be understood that the user may effect manual filling of the tub with any desired quantity of initial wash water by observing the head of wash water in the tub 49 during the initial filling operation.

In view of the foregoing description of the manner in which the user manually fills the tub 49 with hot water, it will be understood that the tub 49 may be filled in a substantially identical manner with either warm water or cold water, the user merely rotating the control dial 130 into its "warm fill" position, or into its "cold fill" position and then lifting the dial 130 into its upper position.

When the control dial 130 is rotated into its "hot fill" position or its "warm fill" position or its "cold fill" position, the control cam C3 operates the switch S3 into its closed position in order to preselect the third electric circuit including the main motor 82 so that operation of the main motor 82 is initiated upon closure of the line switch LS as a result of lifting the control dial 130 into its upper position. This arrangement positively insures operation of the main motor 82 when the control dial 130 is lifted to its upper position and occupies other than its rotary "off" position, whereby the main motor 82 upon operating effects operation of the drain pump 86. Accordingly, the drain pump 86 is always operated during a filling operation of the tub 49 so that should the user inadvertently permit overflowing of the tub 49, the water overflowing from the tub 49 and falling into the tub compartment 28 is pumped by the drain pump 86 through the drain conduit 95 to the exterior. This arrangement positively prevents overflowing of the tub 49 from effecting flooding of the machine 10 and the laundry room in which it is located. Of course, when the control dial 130 is subsequently returned to its lower position the line switch LS is operated to its open position, as previously noted, so that the circuit for operating the main motor 82 is interrupted, ar-

resting operation of the main motor 82 and the drain pump 86.

After the user has effected manual control of the circuit network in the manner described above in order to effect filling of the tub 49 with hot wash water or warm wash water or cold wash water, he may initiate the automatic cycle of the machine 10 merely by rotating the control dial 130 into its first "control" position, slightly beyond the 55° position, and again lifting the control dial 130 into its upper position. When the control dial 130 is rotated into its first "control" position the cams C1 and C2 positively insure operation of the respective switches S1 and S2 into their open positions in order positively to prevent control of the hot water solenoid 129 and the cold water solenoid 128. Also, at this time the control cam C3 operates the switch S3 into its closed position in order to preselect the third electric circuit including the main motor 82. Also, at this time the control cam C4 operates the switch S4 into its closed position in order to preselect the fourth electric circuit including the timer motor 150. Finally, at this time the control cam C5 operates the switch S5 to close the central and lower springs thereof in order to preselect the fifth electric circuit including the clutch magnet 81. At this time when the control dial 130 is raised to its upper position the line switch LS is operated to its closed position connecting the positive line conductor 171 to the bus 172 in order to close the third, fourth and fifth electric control circuits previously prepared. Specifically, operation of the main motor 82 is initiated, whereby the main motor 82 effects operation of the drain pump 86 and the oscillating mechanism 73, as previously explained. Also, operation of the timer motor 150 is initiated, whereby the program selector switch 131 and the control dial 130 are operated step-by-step through their various coordinate "control" positions and ultimately return to their coordinate "off" positions, as more fully explained below. Finally, the clutch magnet 81 is operated effecting clutching of the clutch mechanism 77, whereby the oscillating mechanism 73 effects oscillation of the agitator 67 in order to initiate the washing operation in the machine 10.

The first "control" position of the control dial 130 extends from the 55° position thereof to the 170° position thereof covering an intervening segment of 115° which corresponds to a time interval of 11½ minutes since the timer motor 150 steps the program selector switch 131 and the control dial 130 in the directions previously noted 5° each ½ minute; whereby 10° of rotation of the program selector switch 131 and the control dial 130 correspond to a time interval of one minute. Accordingly, when the user sets the control dial 130 into the first "control" position thereof he brings the desired washing time on the skirt 142 of the control dial 130 into registry with the associated index pointer 141. Thus it will be understood that in the event a full washing time interval of 11½ minutes is desired that the control dial 130 is rotated slightly past the 55° position before it is lifted into its upper position. On the other hand, for example, in the event a shorter washing time interval of 5 minutes is desired, the control dial 130 is rotated to the 120° position before it is lifted into its upper position. Thus the washing time interval is manually adjustable between 11½ minutes and ½ minute at any time interval of ½ minute therebetween.

The washing operation of the machine 10 continues during the preset washing time interval and until the program selector switch 131 is rotated into its 170° position, whereby the control cam C5 operates the switch S5 to disengage the center spring from the lower spring thereof and to engage the center spring with the upper spring thereof, whereby the fifth electric control circuit is interrupted and the sixth electric control circuit is completed. When the fifth electric control circuit, including the clutch magnet 81, is interrupted, the clutch magnet 81 effects operation of the clutch mechanism 77 to its declutched position, whereby further operation of the oscillating mechanism 73 is ineffective to bring about oscillation of the agitator 67. When the sixth electric circuit including the spin motor 97 is thus completed, the spin motor 97 operates to rotate the tub 49 through the drive connection previously described including the fluid drive coupling mechanism 99. When the tub 49 is thus rotated the initial wash water contained therein is centrifuged therefrom through the openings 59 disposed just below the balance ring 56, the wash water being caught in the tub compartment 28 and drained through the drain fixture 94 into the drain pump 86 where it is pumped to the exterior of the machine 10 through the drain conduit 95. The initial wash water is thus discharged from the tube 49 by the centrifugal forces, the clothes being retained therein by virtue of the overhanging flange 57 provided on the balance ring 56. The clothes in the tub 49 are thus spun for a time interval of four minutes in order to effect the complete removal of the wash water therefrom, at which time the program selector switch 131 is rotated into its 210° position; whereby the control cams C1 and C2 effect closure of the respective switch S1 and S2 bringing about operation of the respective solenoids 129 and 128. When the solenoids 129 and 128 are thus operated, warm water is supplied via the inlet conduit 109 into the tub 49 while it is spinning in order to effect a warm water spinning rinsing action upon the contained clothes.

The program selector 131 is rotated into its 215° position 1/2 minute later, whereby the control cams C1 and C2 effect operation of the respective switches S1 and S2 into their open positions so as to de-energize the respective solenoids 129 and 128 for the purpose of interrupting the supply of warm water to the spinning tub 49. The program selector 131 is rotated into its 220° position 1/2 minute later, whereby the control cam C2 effects operation of the switch S2 into its closed position effecting operation of the cold water solenoid 129 and the consequent supply of cold water from the inlet conduit 109 into the spinning tub 49 in order to effect a cold water spinning rinsing action upon the contained clothes. The program selector 131 is rotated into its 225° position 1/2 minute later, whereby the control cam C5 operates the switch S5 to move the center spring out of engagement with the upper contact spring thereof and into a midposition disengaging the lower spring thereof, so as to interrupt operation of the spin motor 97, whereby rotation of the tub 49 is arrested in order to terminate the cold water spinning rinsing action on the clothes contained therein. The program selector switch 131 is rotated into its 260° position 3 1/2 minutes later, whereby the tub 49 is filled to overflowing during the timer interval men-

tioned, the cold water supplied from the inlet conduit 109 into the tub 49 overflowing therefrom via the openings 59 provided below the balance ring 56.

In the 260° position of the program selector 131 the control cam C5 operates the switch S5 to move the center spring into engagement with the lower spring thereof in order to effect re-operation of the clutch magnet 81, whereby the agitator 67 is again oscillated for the purpose of initiating a deep cold water overflow rinsing action upon the clothes contained in the tub 49. This deep cold water overflow rinsing operation continues for a time interval of 1 1/2 minutes; at which time the program selector switch 131 is rotated into its 285° position, whereby the control cam C2 effects operations of the switch S2 into its open position so as to bring about de-energization of the cold water solenoid 128 and the consequent interruption of the supply of cold water from the inlet conduit 109 into the tub 49. After the supply of cold water into the tub 49 is thus cut off, operation of the agitator 67 continues for a time interval of 1/2 minute and until the program selector switch 131 is rotated into its 290° position in order positively to insure that the excess quantity of cold water contained in the tub 49 is overflowed therefrom prior to initiating a final spinning extracting operation of the tub 49, as explained below.

When the program selector switch 131 is rotated into its 290° position, the control cam C5 operates the switch S5 to move the center spring so as to disengage the lower spring thereof and then to engage the upper spring thereof bringing about de-energization of the clutch mechanism 81 and energization of the spin motor 97. Oscillation of the agitator 67 is thus arrested and rotation of the tub 49 is thus initiated, whereby the final rinse water extracting operation of the machine 10 is initiated. The tub 49 continues to spin during a time interval of 7 minutes and until the program selector switch 131 is rotated into its 360° or 0° position constituting its "off" position. During this spinning operation of the tub 49 the cold rinse water contained in the tub 49 and in the clothes therein is extracted, whereby at the termination of the final rinse water extracting operation, the clothes contained in the tub 49 contain only a nominal amount of water, usually each pound of clothes containing approximately one pound of water. At this time the program selector switch 131 and the control dial 130 occupy their coordinate "off" positions indicating that the automatic cycle of the machine 10 has been completed; and all electric circuits are interrupted. Specifically, when the program selector switch 131 is rotated back into its "off" position, the control cams C3 and C4 respectively operate the switches S3 and S4 into their open positions in order respectively to arrest operation of the main motor 82 and to arrest operation of the timer motor 150. Also the cam C5 operates the switch S5 to move the center spring into disengagement with the upper spring thereof in order to arrest operation of the spin motor 97. At this time the cycle of operation of the machine 10 has been completed and the user may again depress the control dial 130 into its lower position in order to effect operation of the line switch LS into its open position so as to interrupt a further common point in all of the electric control circuits. At this time the user may open the cover 107 and transfer the clothes contained in

the tub 49 to a drier in order to prepare the clothes for ironing in the usual manner.

In view of the foregoing explanation of the control of the machine 10 by the control dial 130 and the program selector 131, it will be understood that any one of the operations in the automatic cycle may be selectively repeated either before or after the completion of the cycle of operation of the machine 10 by first depressing the control dial 130, then rotating the control dial 130 into the "control" position corresponding to the desired operation, and then lifting the control dial 130, whereby operation of the machine 10 in the preselected operation in the automatic cycle is initiated. This facility is occasionally useful when it is desired to obtain a somewhat more thorough drying of a heavy load of fabrics in the form of a scatter rug, or the like. For instance, in this case, the final rinse water extracting operation of the machine 10 may be selectively repeated in order to obtain additional time intervals of 7 minutes of water extracting operations. Similarly the final rinse water extracting operation of the machine 10 may be shortened by depressing the control dial 130 when the legend "damp-reg.," just preceding the legend "dry-extra," thereon is associated with the index pointer 147, as shown in Fig. 4. Of course, any of the other operations in the automatic cycle may be similarly repeated, and occasionally this facility is useful where it is particularly desired to obtain a washing operation of longer than 11½ minutes and involving a particularly dirty fabric, such, for example, as work clothes. In this case, the user sets the control dial 130 for a full time interval of 11½ minutes and initiates operation of the machine 10 by lifting of the control dial 130. Thereafter, at the expiration of an appropriate additional time interval, such, for example, as 10 minutes the control dial 130 is depressed and rotated through and back into the beginning of the first control position thereof, such that a time interval of 11½ minutes is again set; whereupon the control dial 130 is again lifted so that the machine 10 may proceed through its normal automatic cycle, as previously explained. In this example, the washing time of the machine 10 has been increased by 10 minutes in order to produce a total washing time of 21½ minutes. Of course, operation of the machine 10 may be arrested at any time either during a manual filling operation or an operation thereof in its automatic control cycle merely by depressing the control dial 130; and thereafter further operation of the machine may be again initiated merely by lifting the control dial 130.

In view of the foregoing it is apparent that there has been provided a semi-automatic clothes washing machine comprising an improved electric control network employing a single control member or dial for the purpose of selectively controlling the various operations of the machine, whereby there is obtained an initial manually controlled filling of the tub with wash water and a following automatic timer controlled cycle, including washing, rinsing, and water extracting operations.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a clothes washing machine including an upstanding casing, an upstanding tub arranged in said casing and mounted for rotation, an upstanding agitator arranged in said tub and mounted for operation, a hot water supply conduit communicating with said tub, a hot water inlet valve operative to open said hot water supply conduit, a cold water supply conduit communicating with said tub, a cold water inlet valve operative to open said cold water supply conduit, said casing being arranged to catch excess water overflowed from said tub incident to filling thereof and water centrifuged from said tub incident to rotation thereof, a drain conduit, and a pump operative to deliver water from said casing to said drain conduit; the combination comprising a program selector switch of the rotary type provided with an "off" position and a "hot fill" position and a "warm fill" position and a "cold fill" position and a plurality of "control" positions, said "fill" positions being arranged between said "off" position and said "control" positions, a shaft mounted for rotation and connected at one end to said selector switch so that selective rotation of said shaft selectively rotates said selector switch into any one of its positions, a single manually operable control knob connected to the other end of said shaft for imparting selective rotation thereto, means responsive to rotation of said selector switch into its "hot fill" position for operating said hot water inlet valve and responsive to rotation of said selector switch into its "warm fill" position for operating both said hot water inlet valve and said cold water inlet valve and responsive to rotation of said selector switch into its "cold fill" position for operating said cold water inlet valve, means responsive to rotation of said selector switch away from its "off" position into any other one of its positions for operating said pump, a timer operative to rotate said selector switch through its "control" positions back into its "off" position and to rotate said knob with said selector switch through said shaft, means responsive to rotation of said selector switch into any one of its "control" positions for initiating operation of said timer and responsive to rotation of said selector switch back into its "off" position for arresting operation of said timer, means responsive to rotation of said selector switch through its "control" positions for operating said agitator and for rotating said tub selectively in order to establish a predetermined operating cycle, and means including said knob for indicating the position of said selector switch.

2. In a clothes washing machine including an upstanding casing, an upstanding tub arranged in said casing and mounted for rotation, an upstanding agitator arranged in said tub and mounted for operation, a hot water supply conduit communicating with said tub, a hot water inlet valve of the solenoid controlled type operative to open said hot water supply conduit, a cold water supply conduit communicating with said tub, a cold water inlet valve of the solenoid controlled type operative to open said cold water supply conduit, said casing being arranged to catch excess water overflowed from said tub incident to filling thereof and water centrifuged from said tub incident to rotation thereof, a drain conduit, and a pump operative to deliver water from said casing to said drain conduit; the combination comprising a program selector switch of the rotary type provided with an "off" position and a "hot fill" position and a "warm fill" position and a "cold fill"

position and a plurality of "control" positions, said "fill" positions being arranged between said "off" position and said "control" positions, a shaft mounted for rotation and connected at one end to said selector switch so that selective rotation of said shaft selectively rotates said selector switch into any one of its positions, a single manually operable control knob connected to the other end of said shaft for imparting selective rotation thereto, first and second electric circuits for respectively operating said hot water inlet valve solenoid and said cold water inlet valve solenoid, said selector switch being rotatable into its "hot fill" position to close said first electric circuit and rotatable into its "warm fill" position to close both said first electric circuit and said second electric circuit and rotatable into its "cold fill" position to close said second electric circuit, a third electric circuit for operating said pump, said selector switch being rotatable away from its "off" position into any other one of its positions to close said third electric circuit, an electric timer motor operative to rotate said selector switch through its "control" positions back into its "off" position and to rotate said knob with said selector switch through said shaft, a fourth electric circuit for operating said timer motor, said selector switch being rotatable into any of its "control" positions to close said fourth electric circuit, a fifth electric circuit for operating said agitator, a sixth electric circuit for rotating said tub, said selector switch being rotatable through its "control" positions selectively to close said fifth electric circuit and said sixth electric circuit in order to establish a predetermined operating cycle, and means including said knob for indicating the position of said selector switch.

3. In a clothes washing machine including an upstanding casing, an upstanding tub arranged in said casing and mounted for rotation, an upstanding agitator arranged in said tube and mounted for operation, a hot water supply conduit communicating with said tub, a hot water inlet valve of the solenoid controlled type operative to open said hot water supply conduit, a cold water supply conduit communicating with said tub, a cold water inlet valve of the solenoid controlled type operative to open said cold water supply conduit, said casing being arranged to catch excess water overflowed from said tub incident to filling thereof and water centrifuged from said tub incident to rotation thereof, a drain conduit, and a pump operative to deliver water from said casing to said drain conduit; the combination comprising a program selector switch of the rotary type provided with an "off" position and a "hot fill" position and a "warm fill" position and a "cold fill" position and a plurality of "control" positions, said "fill" positions being arranged between said "off" position and said "control" positions, a master switch having open and closed positions, a shaft mounted for both rotary and sliding movements and connected at one end to said selector switch and operatively associated with said master switch so that selective rotation of said shaft selectively rotates said selector switch into any one of its positions and selective sliding of said shaft selectively operates said master switch into either one of its positions, a single manually operable control knob connected to the other end of said shaft for imparting selective rotary and selective sliding movements thereto, first and second electric circuits for respectively operating said hot water inlet valve solenoid and said cold water inlet valve solenoid, said selector

switch being rotatable into its "hot fill" position to prepare said first electric circuit and rotatable into its "warm fill" position to prepare both said first electric circuit and said second electric circuit and rotatable into its "cold fill" position to prepare said second electric circuit, a third electric circuit for operating said pump, said selector switch being rotatable away from its "off" position into any other one of its positions to prepare said third electric circuit, an electric timer motor operative to rotate said selector switch through its "control" positions back into its "off" position and to rotate said knob with said selector switch through said shaft, a fourth electric circuit for operating said timer motor, said selector switch being rotatable into any one of its "control" positions to prepare said fourth electric circuit, a fifth electric circuit for operating said agitator, a sixth electric circuit for rotating said tub, said selector switch being rotatable through its "control" positions selectively to prepare said fifth electric circuit and said sixth electric circuit in order to establish a predetermined operating cycle, said master switch being operative into its closed position to close each prepared one of said electric circuits and operative into its open position to open each of said electric circuits, and means including said knob for indicating the position of said selector switch.

4. In a clothes washing machine including a tub adapted to contain wash water and clothes to be washed, a water supply system communicating with said tub, and valve mechanism having open and closed positions and arranged in said water supply system; the combination comprising a program selector switch of the rotary type provided with an "off" position and a "fill" position and a "cycle" position, said "fill" position being arranged between said "off" position and said "cycle" position, a shaft mounted for rotation and connected at one end to said selector switch so that selective rotation of said shaft selectively rotates said selector switch into any one of its positions, a single manually operable control knob connected to the other end of said shaft for imparting selective rotation thereto, means responsive to rotation of said selector switch into its "fill" position for operating said valve mechanism into its open position and responsive to rotation of said selector switch out of its "fill" position for operating said valve mechanism into its closed position, a timer operative to rotate said selector switch through its "cycle" position back into its "off" position and to rotate said knob with said selector switch through said shaft, means responsive to rotation of said selector switch into its "cycle" position for initiating operation of said timer and responsive to rotation of said selector switch back into its "off" position for arresting operation of said timer, means responsive to rotation of said selector switch through its "cycle" position back into its "off" position for selectively operating said valve mechanism and for selectively carrying out washing and rinsing and water extracting operations upon the clothes in said tub in a predetermined cycle, and means including said knob for indicating the position of said selector switch.

5. In a clothes washing machine including a tub adapted to contain wash water and clothes to be washed, a hot water supply conduit communicating with said tub, a hot water inlet valve operative to open said hot water supply conduit, a cold water supply conduit communicating with said tub, and a cold water inlet valve operative

to open said cold water supply conduit; the combination comprising a program selector switch of the rotary type provided with an "off" position and a "hot fill" position and a "warm fill" position and a "cold fill" position and a "cycle" position, said "fill" positions being arranged between said "off" position and said "cycle" position, a shaft mounted for rotation and connected at one end to said selector switch so that selective rotation of said shaft selectively rotates said selector switch into any one of its positions, a single manually operable control knob connected to the other end of said shaft for imparting selective rotation thereto, means responsive to rotation of said selector switch into its "hot fill" position for operating said hot water inlet valve and responsive to rotation of said selector switch into its "warm fill" position for operating both said hot water inlet valve and said cold water inlet valve and responsive to rotation of said selector switch into its "cold fill" position for operating said cold water inlet valve, a timer operative to rotate said selector switch through its "cycle" position back into its "off" position and to rotate said knob with said selector switch through said shaft, means responsive to rotation of said selector switch into its "cycle" position for initiating operation of said timer and respon-

sive to rotation of said selector switch back into its "off" position for arresting operation of said timer, means responsive to rotation of said selector switch through its "cycle" position back into its "off" position for selectively operating both said hot water inlet valve and said cold water inlet valve and for selectively carrying out washing and rinsing and water extracting operations upon the clothes in said tub in a predetermined cycle, and means including said knob for indicating the position of said selector switch.

WALTER P. McCARTY.
